UNITED STATES PATENT OFFICE

107,891

DESIGN FOR AN AIRPLANE

Berthoud C. Boulton, Towson, and James S. McDonnell, Jr., Baltimore, Md., assignors to The Glenn L. Martin Company, Baltimore, Md.

Application April 15, 1937, Serial No. 68,792

Term of patent 14 years

To all whom it may concern:

Be it known that we, Berthoud C. Boulton, and James S. McDonnell, Jr., citizens of the United States and residents, respectively, of Towson, in the county of Baltimore and State of Maryland, and of Baltimore, in the State of Maryland, have invented a new, original, and ornamental Design for an Airplane, of which the following is a specification, reference being had to the accompanying drawings, forming part thereof.

Fig. 1 is a perspective view of the subject airplane in flight.

Fig. 2 is a perspective view differing from Figure 1 in angularity and showing the landing gear in retracted position.

Fig. 3 is a front elevation of the airplane shown in either figure when the landing wheels are extended for ground engagement.

Fig. 4 is a side elevation of Figure 3.

The characteristic features of the design reside in the configuration of the motor cowlings and the empennage section, as well as the association and relation of these elements with the remaining portion of the airplane.

We claim:

The ornamental design for an airplane, substantially as shown and described.

BERTHOUD C. BOULTON.
JAMES S. McDONNELL, JR.
